US00D381325S

United States Patent [19]

McMahan et al.

[11] Patent Number: Des. 381,325

[45] Date of Patent: **Jul. 22, 1997

[54] LASER CONTROLLER

[75] Inventors: **William H. McMahan**, P.O. Box 635, 14966 State Hwy. 410, Robertson, Wyo. 82944; **Jeffrey A. Reed**, Salt Lake City, Utah

[73] Assignee: **William H. McMahan**, Robertson, Wyo.

[**] Term: 14 Years

[21] Appl. No.: 45,751

[22] Filed: Oct. 27, 1995

[51] LOC (6) Cl. 14-02

[52] U.S. Cl. D14/114

[57] CLAIM

The ornamental design for a laser controller, as shown and described.

DESCRIPTION

FIG. 1 is a perspective view of the laser controller showing our new design;

FIG. 2 is a side view thereof;

FIG. 3 is a reverse side view thereof;

FIG. 4 is a front view thereof;

FIG. 5 is a back view thereof;

FIG. 6 is a top view thereof; and,

FIG. 7 is a bottom view thereof.
